CLAIM

(21) Appl. No.: **29/151,940**

The ornamental design for a battery-powered, start-up driving wheel for a gyroscopic exerciser device, as shown and described.

(22) Filed: **Nov. 19, 2001**

DESCRIPTION

(51) LOC (7) Cl. **21-02**

FIG. 1 is a left side elevation view of a battery-powered, start-up driving wheel for a gyroscopic exerciser device, showing my design;

(52) U.S. Cl. **D21/662**; D8/61

FIG. 2 is a right side elevation view thereof;

(58) Field of Search D21/662, 684;

FIG. 3 is a top plan view thereof;

446/233, 235, 236, 259, 234; D8/61, 62

FIG. 4 is a front plan view thereof;

(56) **References Cited**

FIG. 5 is a bottom plan view thereof; and,

U.S. PATENT DOCUMENTS

FIG. 6 is a perspective view thereof.
